CLAIM

I claim, the ornamental design for a branch connection sleeve for power line and ground wire, as shown and described.

DESCRIPTION

FIG. 1 is a left side perspective view of a branch connection sleeve for power line and ground wire, showing my new design;

FIG. 2 is a right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 4 Drawing Sheets
